(57) CLAIM

The ornamental design for a light, as shown and described.

DESCRIPTION

FIG. 1 is a top perspective view of a light design showing my new design;

FIG. 2 is a bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is an enlarged view of the selected portion “9” in FIG. 1; and,

FIG. 10 is an enlarged view of the selected portion “10” in FIG. 1.

Any shading and cross-hatching are not features of the design but are utilized to illustrate the surface contours of the light design in the drawings.

The dash-dot-dash broken lines show the boundaries of the enlarged views and form no part of the claim thereof.
